BEARING CAP REMOVER

Walter A. Sturm, Los Angeles, Calif.

Application April 16, 1945, Serial No. 588,664

1 Claim. (Cl. 24—250)

1

This invention relates to a pulling device for removing bearing caps.

At present there is need for an improved tool to remove main bearing caps and caps for connecting rods, there being at present no tool on the market for this purpose that does not possess certain disadvantages for which this invention provides a remedy. For example, an ordinary hammer may be used to strike blows against the part to be removed in the direction toward which this invention applies traction thereto, but such a tool is far less effective as it does not apply the tractive force axially of the connecting rod from which the cap is to be removed.

The caps are not removable by hand and, due to their snug fit they must, in some way, be hammered off. At the present time there is no tool on the market adapted efficiently to grip opposite sides of the connecting rod cap so that it may be removed by traction directed axially of the connecting rod proper. When this operation is performed by my newly invented device, there is no binding between the bolts and the cap, because this tool withdraws the cap in the axial manner stated.

One of the objects of the present invention is to overcome the defects above pointed out, this being accomplished by supplying the traction in an axial direction.

Other objects, advantages and features of invention will hereinafter appear.

Referring to the accompanying drawing, which illustrates what is at present deemed to be a preferred embodiment of the invention,

Fig. 1 is a side elevation of the device illustrating the application thereof to a connecting rod cap, dotted lines showing the position of the swingable jaw or arm when in a slightly released position, and showing also the position at such time of the yoke and lever whereby said jaw is forced inwardly to the full line, gripping position.

Figs. 2, 3, 4, 5, 6 and 7 are, respectively, cross sections taken on the correspondingly numbered cross section indicating lines on Fig. 1, the arrows associated with each section-indicating line denoting the view point of the observer in each instance.

Referring in detail to the drawing, the pulling device comprises a traction rod 10 carrying at one end a pair of gripping arms 11 and 12, the arm 11 being in a diverging, fixed, preferably integral relation to one end of said rod 10, and the arm 12 being swingably connected to the same end of said rod by a pivot pin 13. Said arms 11 and 12 are shown bowed away from each other

2

in order better to adapt them to embrace between them the piece of work 14 to be operated upon. A bent spring 16, located between the inner end portions of said arms tends to swing outwardly the arm or jaw 12. Said spring is shown attached at one end to arm 11 by a screw 17, the opposite end of said spring abutting against and under a lug 18 projecting from the inner side of the arm 12. Each of the arms 11 and 12 carries a ratchet toothed gripping shoe 19, the teeth 20 of these shoes being directed toward the piece of work 14. In Fig. 2 one of the shoes 19 is shown furnished with a central mounting rib 19a fitted snugly in a groove provided for it in the rounded end portion 19b of the arm 11, it being understood that both shoes and rounded arm ends are alike.

The arms 11 and 12 may be termed elongated gripping jaws, and in order to enable them to perform their gripping function properly the device is provided with a jaw-operating means which is shown as consisting of a bar or yoke 21 with which cooperates an operating lever 22 arranged to apply traction to it, said lever being fulcrumed to arm 11 by means of a pivot pin 23. As well shown in Fig. 6 said yoke 21 has a somewhat tapered end portion through which extends an inclosed slot 25, said slot being of a sufficient size to receive adjustably the arm 12, said arm 12 having along its outer edge a spaced apart series of recesses 26 individually engageable by the shoulder 25a at the outer end of the slot 25.

In order to facilitate application of yoke 21 to the arm 12, the slot 25 in said yoke is first made open at its outer end, and after said yoke has been applied to said arm an insert piece 25b is welded in place to close the outer end portion of the slot, as shown in Fig. 6. This method of assembling is necessary when the arm 12 has the reinforcing 40 enlargement 19b.

From Fig. 3 it is seen that the yoke 21 is channel shaped as viewed in cross section with the open side of the channel directed downwardly. The aforesaid insert piece 25b is so shaped as to provide a shoulder 25a sufficiently narrow to fit readily into the notches 26.

At the opposite end of the yoke 21 a long, longitudinal slot 27 is provided, open at its outer end, this latter slot being adapted to receive loosely 50 the stationary jaw arm 11. Underlying said slot 27 the channel shaped yoke has each of its downwardly directed side portions or flanges furnished with a series of notches 30 with resulting intervening teeth 31, which resemble ratchet teeth be-

cause they have sharp corner portions that are directed toward the opposite end of the yoke.

The operating lever 22 as to its length is of an arcuate shape and is channel shaped in cross section with the open side of its channel directed toward and partly embracing the jaw-forming arm 11 to which the lever is pivoted. The short arm of the lever 22 at the side of its pivot opposite to its handle portion, has fixed to it an operating pin 32 with projecting end portions positioned to cooperate with the two rows of yoke teeth 31 so that the lever may be used to coact with the yoke 21 to draw the swingable jaw arm 12 toward the stationary arm 11 to apply the device to the piece of work as shown in full lines in Fig. 1. It is to be understood that the portion of yoke 21 which is furnished with the slot 27 is, owing to its aforementioned channel shape, provided with a downwardly opening groove which is sufficiently wide to admit loosely between its side portions the short arm of the operating lever 22, but the slot 27 is shown less in width than the width of the underlying portion of said lever. The reversely positioned arrangement of the channel-shaped members 21 and 22 is well illustrated in Figs. 3 and 5, these views also showing how the projecting end portions of the pin 32 cooperate with the toothed edge portions of the yoke 21.

The pivot hole through which passes the pivot 23 of lever 22, is located in a rounded boss 23b that projects from the outer side of the stationary jaw forming arm 11. The channel formation of the pivoted portion of lever 22 is sufficiently deep to allow the handle portion of said lever to swing inwardly a sufficient distance to cause the operating pin, while in engagement with the selected yoke teeth 31, to swing to a past dead center position in relation to a produced line passing through the outer (tapered) end of the yoke and its pivot pin 23, so that the yoke will maintain itself in locked position, leaving the hands of the workman free to operate the conventional, sliding impact weight or hammer 35, the impact of which against the rod head 36 is relied upon to cause the applied tool to withdraw the connecting rod cap 14 from the connecting rod to which it is assumed to be attached.

The teeth 20 of the shoes 19 are shown shaped as ratchet teeth and so inclined as to bite into the piece of work 14 when sudden traction is applied thereto by the impact of said hammer. It is to be understood that the cap-retaining nuts will be completely removed from their bolts before the cap-removing operation is started. Slight deviations from axial traction may be

compensated for by substituting thicker or thinner gripping shoes for the shoes 19 shown in the drawing.

It will be noted that by obtusely deflecting part of the traction rod 10 to form the branch 11 of the bifurcation a rigid, stable mounting means is provided for the swingable arm 12 of the bifurcation, for the latter arm is pivoted to the device at the juncture of said arm 11 with the rod or shank 10, said shank forming a serviceable mounting means for the hammer 35.

It should be understood that the present disclosure is for the purpose of illustration only and that this invention includes all modifications and equivalents which fall within the scope of the subject matter claimed.

What is claimed is:

In a device for detaching bearing caps, a pair of complementary arms pivotally connected at one end and having bearing gripping jaws at their opposite ends, one of said arms having a multiplicity of longitudinally spaced notches, a yoke member disposed transversely of said arms and slidably adjustable longitudinally thereof, said yoke being engageable with the respective notches of said notched arm and having a plurality of notches spaced longitudinally thereof, a curved lever having its intermediate portion pivotally connected to the other arm and operative to rock upon the exterior of said arm, and a pin fixed in one end part of said lever for engaging selected notches of the yoke for clamping the jaws on bearing caps of varying size.
